GAS RESERVOIR

Philip S. Graver, Chicago, Ill., assignor to Graver
Tank & Mfg. Co., Inc., East Chicago, Ind., a
corporation of Delaware

Application December 2, 1944, Serial No. 566,349

3 Claims. (Cl. 48—176)

1

The invention relates generally to tanks and has reference more particularly to a large diameter reservoir of the breather type having an expansion roof capable of varying the volume of the vapor space within the reservoir whereby vapors or gases can be stored in large quantities at low pressures.

An object of the invention is to provide a large diameter gas or vapor reservoir having a movable roof for varying the volume of the storage chamber and which is primarily designed for connection with a number of cone-roofed tanks storing volatile products such as gasoline to permit breathing of said storage tanks.

Another object is to provide a gas reservoir such as described having an expansion roof employing pivoted links for connecting the expansion roof with the shell and which links operate in a manner to stabilize the roof in its up and down movement while maintaining the roof in a substantially horizontal plane, this latter result being effected by the arrangement of the pivoted links which impart slight rotation to the roof simultaneously with the vertical movements thereof.

Another object of the invention is to provide stabilizing means for an expansion roof tank wherein pivoted links for connecting the movable roof with the tank are employed in combination with guiding means located exteriorly of the tank for imparting rotation to the roof simultaneously with the vertical movements thereof, whereby the roof is maintained in a substantially horizontal plane under all conditions.

Another object is to provide a gas reservoir consisting of a stationary shell and a movable expansion roof having sealing relation therewith, and wherein the shell comprises a circular launder supported by the earth in a manner whereby the earth forms the bottom of the gas reservoir and also maintains the circular contour of the launder, thus eliminating the more intricate and expensive reinforcing structure therefor.

Another object of the invention is to provide a gas reservoir of large diameter for economically storing gases or vapors at relatively low pressures, and which is erected in combination with the earth in a manner to adequately support the launder from within the shell, thereby eliminating the circular girders and similar reinforcing structure which large diameter tanks ordinarily require.

With these and various other objects in view, the invention may consist of certain novel features of construction and operation, as will be

2

more fully described and particularly pointed out in the specification, drawings and claims appended hereto.

In the drawings which illustrate an embodiment of the device and wherein like reference characters are used to designate like parts—

Figure 1 is a sectional view showing the gas reservoir of the invention in deflated position with the expansion roof supported directly by the earth;

Figure 2 is a sectional view showing a modified form of the invention wherein internal structure is provided for supporting the roof in deflated position;

Figure 3 is an enlarged sectional view showing the construction of the launder and the arrangement of the pivoted links for stabilizing the roof;

Figure 4 is a fragmentary sectional view taken substantially along line 4—4 of Figure 3 showing the pivotal connection of a link with the roof;

Figure 5 is a sectional view taken substantially along line 5—5 of Figure 4;

Figure 6 is an elevational view taken substantially along line 6—6 of Figure 3;

Figure 7 is a sectional view taken substantially along line 7—7 of Figure 5;

Figure 8 is a sectional view showing another modified form coming within the invention wherein pivoted links and guiding means comprise the stabilizing structure;

Figure 9 is an enlarged fragmentary sectional view of the reservoir shown in Figure 8 illustrating detail the stabilizing means; and

Figure 10 is an elevational view of the structure shown in Figure 9.

Referring more particularly to the drawings, the gas or vapor reservoir of the invention is erected using the earth as the bottom of the reservoir and which also forms the major support for the circular launder forming the shell of the reservoir. The gas space or chamber is thus formed by the expansion roof comprising the top wall, the earth which serves as the bottom of the reservoir, and the circular launder providing

the side walls. A large diameter tank such as herein contemplated would ordinarily require strengthening and reinforcing structure for the side walls, especially when the same comprises the walls of a launder, and thus support a column of liquid. In accordance with the invention the circular launder of the present reservoir is adequately supported on the inside by the earth, thereby relieving the shell walls of the stresses incidental to the support of a column of liquid and eliminating circular girders and similar rein-

forcing structure which would otherwise be required.

In Figure 1 the bottom of the reservoir is formed by the earth fill 10 and which is outlined by a circular trough or recess 11 formed by the sloping bottom wall 12 and the vertical wall 13. The circular shell of the reservoir has contact with and is partly supported by said vertical wall 13, said shell comprising the launder formed by the inner wall 14, the outer wall 15, and the bottom wall 16. At the upper end of the inside wall 14 the same is reinforced by the circular angle member 17, Figure 3, suitably welded thereto, the outer wall 15 likewise being strengthened and reinforced by the angle member 18 and the vertical plates 19, located in spaced relation around the outer periphery of the launder. A plurality of rafters 20 extend radially of the reservoir, being supported at their inner ends by the earth fill 10 and having connection at 21 with a gusset plate 22, which plate is in turn suitably secured by welding to the inside wall 14 of the launder. A number of the gusset plates are joined by the channel members 23 which extend as chords around the periphery of the reservoir.

The expansion roof, indicated in its entirety by numeral 24, is associated with the shell of the reservoir so as to move vertically for varying the space for storing the gases or vapors, whereby said reservoir may be connected to a number of cone-roofed tanks containing a volatile product such as gasoline to permit breathing of said tanks. Said movable roof includes the roof proper 25 of large diameter and which may be formed by welding together a plurality of plates in the well known manner. A girder 26 is suitably welded to the roof 25 around its periphery and said girder adequately reinforces the periphery and maintains the circular contour of the roof during its vertical movements. The circular angle member 27 joins the dip ring 28 to the girder and accordingly said dip ring, girder and roof constitute a unit with the roof 25 resting directly on the earth fill 10 when in deflated position.

It will be observed that the dip ring 28 has location within the launder formed by the walls 14 and 15 and for sealing the roof with respect to the shell the launder contains liquid such as water or oil. The roof may move vertically of the shell for almost the length of the dip ring 28 while maintaining sealing relation therewith. The length of the dip ring therefore determines the lift of the expansion roof and for the gas reservoir of this invention said lift will probably not exceed ten or twelve feet, which is sufficient for all practical purposes considering the large size of the gas reservoir which may have a diameter ranging from one hundred to two hundred and fifty feet. The weather hood 30 is attached to the outer edge of the roof girder and said weather hood has its lower edge supported against the outer wall 15 of the launder by means of rollers 31 carried by the members 32. In operation of the expansion roof the rollers 31 contact the vertical plates 19 to thus limit upward movement of the roof. The plates 19 therefore determine the full inflated position of said roof.

The vertical movements of the expansion roof are stabilized and the roof is maintained in a substantially horizontal plane during said movements by the links 33. Said links have pivotal connection at one end with the expansion roof and at the other end with the inside wall 14 of the launder. Figures 4 to 7 inclusive show details of the pivot connections. For attaching the

links to the roof, the roof girder 26 is provided with depending plates 34, Figures 4 and 5, suitably spaced for receiving the journalling member 35. One of said plates 34 is reinforced by the angle plates 36 which are also secured to the plate girder 26. The journalling member 35 is shown in section in Figure 7, the same having bifurcated ears 37 which receive the plate extension 38 secured to and projecting from the upper end of the link 33. The pivot pin 40 connects the journalling member 35 with the plates 34 and by means of the bolt 41 the plate extension 38 and the link 33 are pivotally joined to the bifurcated ears 37 of said member. The construction forms a universal joint and accordingly each link may move in two planes at right angles to each other.

The links are also connected at their opposite ends by universal joints to the shell of the reservoir. The plate brackets 42, reinforced by the gusset plate 43, are suitably welded to the inside wall 14 of the launder. Plates 44 are secured in spaced relation to each plate bracket for receiving the journalling member 45 held in place by the pin 46. The bifurcated ears 47 of said journalling member receive the plate extension 48 secured to and projecting from the lower end of the link 33. The pin 49 pivotally joins the plate extension to said bifurcated ears. The universal joints are required since the expansion roof has slight rotation simultaneously with its up and down movements. Lateral movement of the links produced by rotation of the roof is permitted by their pivotal connection with the bifurcated ears of the journalling member.

As shown in Figure 1, the earth fill 10 around the periphery of the expansion roof is removed to provide a space sufficient to accommodate the stabilizing arms and the supporting structure for the rafters. The gas or vapor is supplied to the reservoir by means of the supply line 50 which may extend for some distance around the trough 11. The vapor lines 51 connect therewith at intervals and said lines extend upwardly into the peripheral space under the expansion roof. When gases or vapors are admitted to the reservoir by said lines 51 the stabilizing arms 33 will come into action, causing slight rotation of the roof as the same moves upwardly. This action will effect an even rise of the roof throughout its extent of vertical movement and thus the roof is maintained in a substantially horizontal plane at all times.

In Figure 2 a modification is disclosed wherein in the earth fill 60 forming the bottom of the reservoir is flat throughout its extent and wherein internal supporting structure is provided for supporting the roof in deflated position. In this modification the level of the bottom 60 is below that of the surrounding earth. At suitable intervals uprights 61 and 62 are provided, having connection with the rafters 63 to form the necessary internal supporting structure for the expansion roof.

In the modification shown in Figures 8, 9 and 10 the gas reservoir is located on a level section of ground 70 and instead of excavating, as in Figures 1 and 2, a circular mound of earth 71 is formed, the same outlining the bottom 72 of the gas reservoir and providing the vertical wall 73. The circular shell of the reservoir has contact with and is partly supported by said vertical wall 73. Said shell forms the launder for the expansion roof and includes the inner wall 74, the outer wall 75, and the bottom wall 76. Around the upper edge of the inside wall 74 the launder

is reinforced by the circular angle 77, the outer wall 75 likewise being strengthened and reinforced by the angle member 78. A plurality of rafters or roof supporting members 80 extend radially of the reservoir, being supported at their outer ends by the gusset plates 81, which plates are in turn suitably secured as by welding to the inside wall 74 of the launder. Within the reservoir the rafters 80 are supported at intervals by the vertical posts 82 which rest on the earth 72 comprising the bottom of the reservoir.

The expansion roof 83 is associated with the launder so as to move vertically for varying the vapor space for storing the gases or vapors. Said movable roof includes the roof proper 84 which may be formed by welding together a plurality of plates in the well known manner. A girder 85 is suitably welded to the roof 84 around its periphery and the girder adequately reinforces the periphery of the roof and maintains the circular contour of the same during vertical movement. The circular angle member 86 joins the dip ring 87 to the girder and accordingly the dip ring, girder and roof comprise a unit which moves together, the roof resting directly on the rafters 80 when in deflated position. In this deflated position it will also be observed that the girder 85 is supported partly by the angle members 78 and partly by the gusset plates 81.

The dip ring 87 has location within the launder formed by the spaced vertical walls 74 and 75. For sealing the roof with respect to the launder the same contains a liquid such as water or oil and accordingly the expansion roof may move vertically of the launder for the full length of the dip ring while maintaining sealing relation therewith. The rain shed skirt 88 is attached to the outer edge of the roof girder 85 and thus said rain shed skirt also forms a part of the roof, having movement therewith. At spaced intervals around the rain shed skirt the same is strengthened and reinforced by means of vertically extending members 89 suitably secured thereto. At these locations additional means are provided for adding rigidity to the rain shed skirt and for supporting the same from the roof. A radially extending roof member 90 projects beyond the girder 85 at spaced intervals around the circumference thereof and is suitably secured at its outer projecting end to a pair of angle members 91. The angle members extend downwardly and inwardly and connect as at 92 with the lower edge of the rain shed skirt, as clearly shown in Figure 9. In this manner the rain shed skirt is adequately strengthened and a secure connection is provided with the expansion roof.

The additional strengthening of the rain shed skirt is required since rollers 93 are carried thereby, having location at spaced intervals around the lower edge of the skirt. Each roller is journaled by a caster 94 rotatably carried by the built-up bracket structure 95 suitably secured as by welding to the lower edge of the rain shed skirt. As best shown in Figure 3 each roller has rolling contact with guiding means 96 in the form of guide rails fixed to the exterior wall 75 of the launder. It will be observed by reference to Figure 10 that each guide rail 96 is diagonally positioned on the outer wall of the launder so as to form an angle with the vertical. Accordingly, as the expansion roof moves vertically limited rotational movement will be imparted to the roof as a result of the rolling contact which the rollers 93 have with their guiding rails 96.

This limited rotation of the expansion roof simultaneously with vertical movement thereof is desirable when stabilizing links 97 are employed to connect the roof and the launder. This action of the stabilizing links is to maintain the roof in a substantially horizontal plane during vertical movement of the same, and in the modification of Figure 8 this action is additionally controlled by the rollers and guide rails. The links are located between the launder and the rain shed skirt 88, which therefore provides a weatherhood for said links, and said links are positioned in spaced relation around the periphery of the roof. Each link 97, as shown in Figures 9 and 10, has pivotal connection at one end with the expansion roof and at its other end with the outside wall 75 of the launder. For attaching the links to the expansion roof a member 98 is provided. For attaching each link to the launder bracket structure 99 is suitably welded to the outside wall 75. The details of the pivot connections are the same as shown and described in connection with Figures 4 to 7 inclusive and reference is made to those figures.

The gas or vapor is supplied to the reservoir of Figure 8 by means of the supply line 100 having the vapor conduits 101 connecting therewith at intervals and which are located in the earth so as to extend within the reservoir. When gases or vapors are admitted to the reservoir by said conduits 101 the stabilizing links or arms 97 will function to stabilize the vertical movement of the roof, causing the roof to move to a like extent at all points around the periphery of the same. Accordingly, the roof is maintained in a horizontal plane during upward and downward vertical movement. The action of the stabilizing arms 97 is to cause rotational movement of the roof simultaneously with vertical movement thereof. The action of the rollers 93 on the guide rails 96 also has the effect of causing the roof to rotate as it moves vertically, which supplements the action of the stabilizing arms. The combination of stabilizing arms and roller guiding means is satisfactory in all respects for large diameter tanks where the lift does not exceed 10 or 12 feet. The structure is economical, performs its intended function in a satisfactory manner, and requires a minimum of servicing expense.

This application is a continuation-in-part of my copending case Serial No. 512,907, filed December 4, 1943, entitled Gas reservoir, and now abandoned.

The invention is not to be limited to or by details of construction of the particular embodiment thereof illustrated by the drawings as various other forms of the device will of course be apparent to those skilled in the art without departing from the spirit of the invention or the scope of the claims.

60 What is claimed is:

1. In a gas reservoir, a tank comprising upright circular walls spaced apart to provide a launder, a movable roof for said tank having a dip ring depending within the launder for sealing the roof with respect to the tank while permitting vertical movement of the roof to vary the vapor space within, a rain shed skirt depending from the periphery of the roof and encircling the launder, and means guiding the roof during said vertical movement thereof including diagonally extending guide rails fixed to the exterior wall of the launder in spaced relation and at the same angle with respect to a horizontal plane as determined in one direction around the launder, and rollers carried by the lower end of the rain

shed skirt and having contact with said guide rails respectively.

2. In a gas reservoir, a tank comprising upright circular walls spaced apart to provide a launder, a movable roof for said tank having a dip ring depending within the launder for sealing the roof with respect to the tank while permitting vertical movement of the roof to vary the vapor space within, a rain shed skirt depending from the periphery of the roof and encircling the launder, guide rails fixed to the exterior wall of the launder in spaced relation and extending at the same angle with respect to a horizontal plane as determined in one direction around the launder, rollers adapted to contact said guide rails respectively, and means securing said rollers to the lower end of the rain shed skirt in spaced relation around the same, whereby said roof during vertical movement thereof is guided in a manner to cause limited rotation of the roof simultaneously with said vertical movement.

3. In a gas reservoir, a tank including upright circular walls spaced apart to provide a launder, a movable roof for said tank having a dip ring depending within the launder for sealing the roof with respect to the tank while permitting vertical movement of the roof to vary the vapor space of said reservoir, pivoted links connecting the roof and the launder and being mounted at an angle of approximately 90° to a radius of the roof and all said links forming the same angle with respect to a horizontal plane as determined

in one direction around the launder, said links having spaced location around the circumference of the launder and including universal joints at the pivotal connections with the roof and launder, respectively, whereby said roof has limited rotation simultaneously with the vertical movement thereof, a rain shed skirt depending from the periphery of the roof and encircling the launder, guide rails fixed to the exterior wall of the launder in spaced relation around the same and extending at the same angle with respect to a horizontal plane as determined in one direction around the launder, and rollers carried by said rain shed skirt and having contact with the guide rails respectively for guiding said roof during vertical movement thereof.
